METHOD AND MOLD FOR FORMING PLASTIC INSIGNIA

Roy J. Renholts, Oakland, Calif., assignor to
Friden Calculating Machine Co., Inc., a corporation of California

Application August 5, 1949, Serial No. 108,849

4 Claims. (Cl. 18—30)

1

This invention relates to the affixing of plastic name plates, trade-marks, or other insignia, upon an article.

An important object of this invention is to provide a method and means for molding trade-marks, name plates, or other indicia on the cover of an article in such a manner as to make its accidental removal impossible and still to avoid any damage to the plate upon which the indicia is applied.

Another object of this invention is to provide a method and means for applying letters or individual characters forming an insignia to an article in one simple operation.

A still further object of this invention is to provide a method and apparatus for affixing individual letters or insignia to a bearing plate without injuring or marring the painted surface of the plate.

These and other objects of this invention will be apparent from the description and claims which follow.

The invention will be readily understood from reference to the drawings in which—

Fig. 1 illustrates the outside, or visible, portion of a mark as applied according to my invention.

Fig. 2 shows the reverse side of the mounting plate.

Fig. 3 is a cross-sectional view of the insignia of my invention, such as taken along the plane indicated by the line 3—3 of Fig. 1.

Fig. 4 is a cross-sectional view of the dies in position for moulding an insignia on a mounting plate, such as taken along the plane indicated by the line 4—4 of Fig. 1.

Briefly, my invention comprises providing a plurality of apertures through the plate or article within the outline of the insignia, pressing a pair of opposed dies against the two sides of the plate (the die on the outside being formed in the shape of the characters desired), and injecting a plastic material into the other die, through the apertures, and into the outside die. In this manner the characters are formed in situ, are separated on the outside but have a single locking strip along the back. Obviously, the formation of such an insignia takes only a few seconds, and can be applied without injury to the article as will hereinafter be described.

The closest prior art with which I am familiar is the pre-forming of a plastic insignia provided with two or more bosses which are manually inserted through holes in the mounting plate. After manual insertion of the bosses in the holes in the mounting plate, the assembly is turned over

2

and heat treated to expand the end of the bosses and thus in effect rivet the plastic insignia onto the metal plate. This prior art treatment has the disadvantage that there is considerable waste of plastic material in the pre-forming of the insignia in the fact that several handlings are necessary, which increases the cost thereof and in the fact that the insignia is attached to the plate in only two or three places so that it can readily be torn off or broken, as it is possible to catch a thread of a dustcloth under such insignia and loosen it from the cover plate. In my invention I form the insignia in situ in a single operation which takes perhaps ten seconds. I, therefore, avoid the extra handling of the plate and of the insignia. Also, in the old art, the holes through the plate had to be accurately positioned and carefully reamed as a burr would prevent insertion of the boss through the hole, while with my invention burrs and the like serve to anchor the insignia more firmly. More important, with my invention, the characters can be separated as shown in Fig. 1 which gives a more pleasing appearance than is possible when an insignia or name is written in script or mounted upon a backing plate.

A still further advantage of my invention lies in the fact that the several characters fit very tightly against the article—in fact with what may be termed a "pressure" fit. Each character is so firmly affixed to the metal plate so that it is not only impossible to injure them by dusting, but it is impossible to insert a knife blade between the character and the plate. The only way in which the characters of my invention can be broken from the mounting plate is by use of a pair of pliers to twist them off or by use of a chisel.

In its preferred form, my invention will be utilized to affix a plurality of separate characters, letters, or insignia to an article or to the plate enclosing it. This permits the trademark or trade-mark, which is customarily used for this purpose, to show a plurality of separated letters, or characters, each of which appears in its individual, or disconnected, form, although the entire group operates as a single insignia. It will be understood, however, that my invention is also applicable to the affixing of a single letter, character, or insignia to an article.

In my invention the several insignia, or characters, which comprise the name, or other indicia, are mounted on a plate 10 which, as shown in Fig. 3, may be coated with a painted finish 11. I have used my invention with good results on

the affixing of a name to a cover plate painted with a wrinkle finish paint, the entire name being affixed with a single simple operation and without injury to the finish.

Cover plate 10 is provided with a plurality of apertures 15 arranged within the outline of the respective characters which comprise the complete insignia. These apertures may be formed by stamping during the forming of the plate 10, or may later be drilled, or otherwise provided in the 10 plate.

With my invention the holes 15 can be of any size or shape and do not have to be reamed. As a matter of fact, any burrs that may stick to the holes as originally punched or drilled, merely add 15 to the strength of the bond between the mounting plate and the character.

A pair of opposed dies are temporarily applied to the plate 10 in a zone in which the plate is of substantially uniform thickness, as shown in Fig. 20 4. The outside die 30 is provided with a plurality of separated, or disconnected, cavities 31 corresponding to the characters 20 which it is desired to mount on the outside of the plate. Normally these characters 20 will be letters, or other characters, arranged to form a complete name or trademark. Against the back of the plate 10 a second die 32 is applied, in opposition to the die 30. Preferably the die 32 will be provided with a single cavity, or channel, which encompasses all of the apertures 15. An injection duct 34 leads to the inner die cavity. The two dies are in opposed relationship on opposite sides of the plate 10 and the plate 10 is so positioned in respect to them that the apertures 15 lie within 35 the outlines of the cavities 31 in the die 30 and within the outline of the channel 33 in the die 32. A fluid plastic material is then injected through the duct 34 with sufficient pressure to force the plastic material through channel 33 through 40 the apertures 15 and into the disconnected cavities 31. Normally such material hardens rapidly and the dies can be removed immediately. I have used my invention with a variety of plastics and have had very satisfactory results with all of 45 them.

Aluminum is a customary material for forming the cover plates 10 as it is light and easily manufactured into desired shapes. A customary working pressure in such injection molding is ten tons or thereabouts. It is obvious that such a pressure upon a sheet of light aluminum would radically deform it, if not completely shear it in two. In order to avoid injury to the mounting plate I provide a plurality of spacers 41 separating the two dies by the exact thickness of the material used in the mounting plate 10. Thus, while the dies are held in spaced relationship by a force sufficient to overcome the pressure of ten tons with which the plastic is injected, the pressure of each die against the plate is much less. In fact, the plate is held firmly between the dies, but the pressure against the plate is insufficient to either deform the plate or to injure the painted surface 11 thereon. As a matter of fact, the characters are formed with a firm fit of the dies against the plate, especially when a wrinkle paint finish is used. When a wrinkle paint finish is used, the depressions in the paint finish, which may be .001 of an inch deep act as gas vents to 70 permit the escape of gas from the melted plastic. Thus, it is unnecessary to provide the die 30 with gas vents as would ordinarily be required. Obviously, the dies should be accurately formed to fit the curvature of the mounting plate 10.

I have found that better results are secured if the die 30 is formed so as to provide a very narrow edge 42 around the insignia. As shown in Fig. 4, the die contacts the plate only over a narrow marginal area, and has somewhat the effect of a knife edge around the insignia. I have found that a width of $\frac{1}{16}$ to $\frac{1}{64}$ of an inch is suitable for this purpose. When the die is formed with such a narrow edge in contact with the plate 10, there is less likelihood of deforming the plate. In addition the edges are thin enough to permit the escape of gas from the interior of the mold through the crevices in the wrinkled finish. This edge need not extend around each individual character. It is sufficient if it extends around the entire insignia. Thus it is necessary to relieve the die between the separate characters.

I might mention in this connection that when the plate and the newly formed insignia are removed from the mold, it will be seen that the heated plastic has softened the paint in that portion covered by the die. It is for this reason that I desire the edge of the die to be as small as possible. However, after cooling for an hour or so the paint has returned to practically its original condition and color and it requires a very close scrutiny to determine any difference between the color of the paint immediately adjacent the insignia and that in the other part of the plate.

It is known in the prior art that the mold can be finished in a variety of manners so as to give a variety of pleasing effects on the finished character without the necessity of further treatment. Thus I am able to quickly form in situ an insignia of very pleasing appearance.

In my invention it is possible to replace an insignia without refinishing the mounting plate, as sometimes is necessary when the insignia is damaged by an extreme force or fire. With my invention, the insignia can be removed by breaking the backing plate 21 away from the plate with a chisel and then driving each of the integral plastic pins through the apertures 15 by a suitable punch. With my invention there is no adhesion between paint and plastic so the painted finish is not injured by such removal. After removing the insignia, a new one can be molded on the plate without the necessity of refinishing the outside of the mounting plate.

This process provides a simple method and means for applying a plurality of separated, or disconnected, characters, or letters, to form an insignia. It is obvious that the several characters 20 extend through the plate itself and are integral with the backing piece 21, whereby the individual characters cannot be removed from the mounting plate except by breaking of the connecting bars, or stems, which extend through the apertures 15.

Another advantage of my invention lies in the fact that the various characters can be smaller than is otherwise practical. In the prior art the name plate or script had to be fairly large size in order to provide ease in handling. With my invention, handling of a preformed name is unnecessary, so that the only practical consideration is that the holes or apertures 15 through the mounting plate be sufficiently large to provide for ready flow of plastic material therethrough. With the heat and pressures customarily used I have found that any hole larger than .020 of an inch will normally be satisfactory. With this limitation the individual characters 20 can be

of any size to suit one's taste, so long as they are larger than an aperture of .020 of an inch.

I claim:

1. The method of affixing separated characters of an insignia to an article which comprises providing a plurality of apertures through the article within the outline of each of the characters in a zone in which the article is of substantially uniform thickness, applying a die formed with disconnected characters against one side of the article at said zone and a second die formed with a single channel against the other side of the article with said channel being substantially parallel to said plate and substantially coextensive with said zone, said dies being separated by an external spacing means a distance equal to the thickness of the article and the first die contacting said plate only over a narrow marginal area around said insignia, injecting a hardenable plastic material into the second die under sufficient pressure to force such material through said second die, said apertures, and into the several disconnected portions of said first die, and thereafter removing said dies.

2. The method of affixing insignia to an article which comprises providing a plurality of apertures through the article within the outline of the insignia in a zone in which the article is of substantially uniform thickness, applying a die formed with the insignia against one side of the article at said zone, said die engaging said article with a narrow face of a width of the order of about $\frac{1}{64}$ to about $\frac{3}{32}$ of an inch, applying a second die formed with a concavity substantially coextensive with said zone and sufficiently large to cover said apertures against the inside of the article at said zone, injecting a hardenable plastic material into the second die under sufficient pressure to force such material through said second die, said apertures, and into the said first die, and thereafter removing said dies.

3. A compound die for affixing an insignia of hardenable plastic material to a perforated article of stable material of substantially uniform thickness which comprises an outer die element

adapted to contact the outer face of said article, said element having formed therein the separated characters of such insignia and having a narrow face thereon of a width of the order of about $\frac{1}{64}$ to about $\frac{3}{32}$ of an inch immediately adjacent said insignia, and an inner die element having a single channel in opposed relation to the characters of said face element, said channel being substantially coextensive with said characters considered collectively, means for injecting plastic material into the channel of said second element and spacing means separating said elements by the thickness of said article.

4. The method of affixing characters of an insignia to an article provided on one side with a wrinkled paint finish which comprises providing a plurality of apertures through the article within the outline of each of the characters, applying a die formed with characters against said one side of the article and a second die formed with a single channel against the other side of the article, said dies being separated by an external spacing means a distance equal to the thickness of the article and the first die contacting the wrinkled paint finish of said plate only over a narrow marginal area around said insignia, injecting a hardenable plastic material into the second die under sufficient pressure to force such material through said second die, said apertures, and into the several disconnected portions of said first die to thereby expel gas from said dies through the vents provided between said wrinkled paint finish and said narrow surface of said first die, and thereafter removing said dies.
